UNITED STATES PATENT OFFICE

2,443,912

INTERNAL-COMBUSTION ENGINE

Rasmus M. Hvid, Wilmette, Ill.

Application January 22, 1943, Serial No. 473,176

7 Claims. (Cl. 123—32)

1

This invention relates to internal combustion engines, more particularly to engines of the type wherein the fuel, such as oil or the like, is discharged into a cup in which ignition occurs and which has restricted communication with the combustion chamber, so that the resulting explosion in the cup causes atomized fuel particles to discharge from the cup into the combustion chamber for complete burning to produce the power stroke, and the invention has for an object the provision of improved engines of this character.

In such oil-operated engines heretofore known, air is drawn into the cylinder and heated therein by compression to a very high degree, a portion of the heated air entering the cup through restricted communicating holes so as to ignite the fuel oil in the cup and cause the desired explosion therewithin. The high compression required for such operation results in relatively high explosion pressures within the cylinder, and accordingly such engines must be heavily constructed and require exceptionally good materials and excellent workmanship.

It is an object of the present invention to provide an internal combustion engine of the type utilizing an ignition cup, wherein the ignition of the fuel oil in the cup is independent of the compression pressure, whereby suitably low compression pressures may be employed resulting in low explosion pressures in the cylinder.

It is a still further object of the invention to provide, in an internal combustion engine utilizing an ignition cup, an improved fuel valve and operating means therefor, whereby reliable and accurate control of the engine may be obtained.

For a more complete understanding of the invention reference should now be had to the drawings, in which:

Fig. 1 is a top plan view of an internal combustion engine embodying the present invention, a portion of the rocker arm mechanism being shown in section more clearly to illustrate the structural details;

Fig. 2 is a vertical sectional view taken substantially along the line 2—2 of Fig. 1 with respect to the valve-operating gear and through substantially the center line of the upper portion of one of the cylinders;

Fig. 3 is a detail view of the improved fuel valve shown in Fig. 2, taken at substantially right angles to the showing in Fig. 2 and facing the spray holes 6 in the cup;

Fig. 4 is a top plan view of the fuel valve shown in Fig. 2;

2

Fig. 5 is a vertical sectional view of the fuel valve taken substantially along the line 5—5 in Fig. 3;

Figs. 6 and 7 are transverse sectional views taken along the lines 6—6 and 7—7 respectively of Fig. 5; and

Fig. 8 is a similar transverse sectional view taken along the line 8—8 of Fig. 3.

Referring now to the drawings, the invention

- 10 is shown in Figs. 1 and 2 as applied to a four-stroke cycle internal combustion engine having a pair of cylinders 64, one of which is shown in section in Fig. 2. It is of course understood, however, that the invention is not limited to the 15 particular engine shown, but may be embodied generally in engines having any desired number of cylinders and employing different operating cycles. As shown, the cylinder 64 is provided with a piston 65 which reciprocates therein 20 in the usual manner and which provides, in the upper part of the cylinder 64, a compression or clearance space 66. The clearance space 66 is so proportioned that the temperature of the air charge, caused by its compression in the cylinder during operation, will be less than that required to ignite the fuel. At its upper end the cylinder 64 is provided with an air intake valve 68, and in addition there is provided, adjacent one edge of the upper end of the cylinder, a fuel cup 5 which 25 forms a part of the improved fuel valve to be described in detail hereinafter, the cup 5 communicating with the compression space 66 through suitable spray holes 6 formed in one wall of the cup. Opposite the holes 6 the cup 5 is 30 provided with an opening 7 through which extends the inner end of a suitable spark plug 7a, the spark plug being mounted in the cylinder head of the engine as shown.

- 35 In Fig. 2 the piston 65 is shown as moving 40 downwardly on the intake stroke, and the valve 68 is open so that a charge of air is being drawn into the cylinder through a suitable supply passage. At the same time a charge of fuel, and a limited quantity of air, will be drawn into the 45 cup 5 through the improved fuel valve in a manner to be fully described hereinafter. The charge of fuel entering cup 5 will be partially atomized and vaporized and some of the oil charge will spread over the bottom of the cup as a film 50 thereon.

- 55 On the following compression stroke, all of the valves will of course be closed, and at the proper point in the stroke, or near the upper dead center position of the piston 65, the spark plug 7a will be energized through the usual electrical ignition

system (not shown) so as to ignite the charge of fuel in the cup 5. The resulting explosion will cause the entire remaining charge of oil, or fuel, contained in the cup 5 to be sprayed in atomized and vaporized condition through the holes 6 into the compression space 66 of the cylinder. The direction taken by this spray of atomized fuel is indicated by the line 67 in Fig. 2, and it will be noted that the holes 6 are so directed that the clearance or compression space in the cylinder is covered efficiently by the spray issuing from holes 6.

Complete burning of the atomized and vaporized fuel in the cylinder thereupon takes place and the expansive force of the gases resulting therefrom forces the piston 65 downwardly on the power stroke. Since the cup 5 is of relatively small volume, there will always be sufficient fuel in the ignition cup to insure a mixture rich enough in quality to ignite when the spark plug is energized, even though the engine may be operated at an exceptionally low load and speed.

Referring now to Figs. 3 to 8, inclusive, the details of the improved fuel valve for supplying controlled quantities of fuel to the ignition cup 5 will be described. The fuel valve body 1 is formed, as shown best in Figs. 3 and 4, to provide a pair of outwardly extending lugs 2 in which suitable holes are provided to accommodate studs in the cylinder head 11. The portion of the fuel valve body 1 above the lugs 2 is formed, as shown best in Figs. 3 and 4, to provide a pair of upwardly extending flanges 3 and 4, while the portion of the body beneath the lugs 2 is substantially cylindrical. This cylindrical portion of the fuel valve body is provided with a reduced end portion which extends into the fuel cup 5 and engages the upper surface of a valve piece 13 which rests on a suitable internal shoulder within the valve cup. As shown best in Fig. 3, the upper part of the valve cup 5 is provided with an aperture 8 through which a suitable positioning screw 9 extends into the valve body 1 to fix the cup in proper relation to the valve body.

As shown in Fig. 2, when the valve body 1 is properly positioned in the cylinder head 11, suitable studs 62 extend through the apertures in the lugs 2 and the valve body is held down by suitable nuts 63 which engage the studs 62. When the nuts 63 are tightened down, the outer conical surface of the cup 65 is drawn tightly against a corresponding conical surface machined in the cylinder head 11, so that proper positioning and gas tightness of the fuel valve body 1, the cup 5, the valve piece 13, and the cylinder head 11 are assured. Adjacent its upper end, the cylinder head 11 is provided with a groove 12 for receiving a positioning pin 16 (Fig. 5) which extends outwardly from the cylindrical portion of the valve body 1, groove 12 and pin 16 being thus the means for positioning valve body 1 relative to cylinder head 11.

The valve piece 13, which is located within the cup 5, is suitably drilled as shown to receive an air valve 14, and is likewise formed to provide a valve seat for a suitable fuel valve 15, and to provide a delivery passage 16 extending downwardly from the fuel valve seat to the interior of the cup 5. The stem of the air valve 14 extends, as shown, upwardly through a suitable air passage 17 in the valve body 1, which passage is enlarged at its upper end to provide a space for accommodating the valve spring 18. As shown in Fig. 6, the space 18 communicates with the atmosphere, outside of the valve body 1, by a

suitable passage 19 which extends therethrough.

The governing fuel valve 15 extends, with a close operating fit, through a suitable passage 20 in the valve body 1, and is provided at its lower end with a reduced portion 21 which terminates in a tapered lower end adapted to co-operate with the valve seat formed in the valve piece 13. Communicating with the lower end of the passage 20, at the portion into which the reduced end of the valve 15 extends, is a transverse passage 30, the other end of which connects with a vertical passage 29 which extends upwardly through the valve body 1 substantially parallel to the passage 20. At its upper end the passage 29 connects with a drilled passage 28 which in turn connects with a second drilled passage 27, the passages 27 and 28 extending transversely through the valve body and being provided with screwed plugs 31 and 32, respectively, for tightly closing the outer ends thereof. Intermediate its length the passage 27 intersects a vertical passage 26 in the valve body, to the upper end of which is fitted an oil supply tube 33.

As previously indicated, the fit between the fuel governing valve 15 and the passage 20 must be sufficiently close so that only a minimum amount of fuel leakage can occur. This leakage must not exceed, during a cycle of the engine, the amount of oil required for a power stroke when the engine is idling. There will in operation, of course, always occur some slight leakage of oil, because the pressure head of the fuel oil is higher than atmospheric pressure, and, accordingly, the passage 20 is provided near its upper end with an enlarged section 23 through which extends a drilled hole 24 which communicates with the space 18. The outer end of the drilled hole 24 is plugged tight by a screwed plug 25, and any leakage of oil which occurs upwardly through the passage 20 will drain through the passage 24 into the space 18, from where it will be carried, on each suction stroke of the engine, into the cup 5 by the air stream passing the valve 14.

Supported between the spaced flanges 3 and 4 of the valve body 1 is a cross piece 50 which is secured in place by suitable screws 51, as shown best in Figs. 4 and 5, and the oil supply tube 33, which extends upwardly between the flanges 3 and 4, is held in tight contact with the upper end 50 of the passage 26 by means of a screw 34 which extends through the cross piece 50. Thus the top and bottom ends of the supply tube 33 are made oil-tight, and a suitable oil supply tube 35, which extends from a suitable source, not shown, but 55 which may be an overhead fuel tank or a low pressure pump, connects with the oil supply tube 33, intermediate its ends. It will be apparent, as the description proceeds, that only a low head of oil is required. In the two-cylinder engine shown for purposes of illustration, a second oil tube 36 is provided which extends from the fitting 33, as shown in Fig. 1, to a similar fitting for the other cylinder, so that the fuel supply is thus connected with both of the fuel valves.

65 The upper end of the stem of the air valve 14 is threaded, as shown, to co-operate with an internally threaded guide piece 37 which has a close operating fit in the passage 18, and a pin 38, adapted to be inserted through the valve stem 70 after assembly, prevents the piece 37 from coming unscrewed from the valve 14. A flat washer 39, which serves as a pusher piece for the valve-operating arm to be hereinafter described, is fitted to the upper end of the guide piece 37, and when 75 the operating arm is not pressing down upon this

pusher piece the valve spring 18 maintains the valve 14 in tight engagement with its seat.

In order properly to position the governing fuel valve 15 for operation with respect to its co-operating seat, the upper end of the valve is provided with a threaded portion 40 and a squared end portion 41, the latter portion being adapted to accommodate a wrench. As shown best in Fig. 5, the threaded part 40 co-operates with an internally threaded sleeve 42 which, at its top end, is formed to provide a tapered, externally threaded portion 43. This tapered portion 43 is provided with a plurality of slots 44 and is engaged by a nut 46. When the nut 46 is loose on the threaded portion 43, the valve 15 may be turned in relation to the sleeve 42 so as to effect longitudinal adjustment therebetween. Tightening the nut 46 is, of course, effective, by inward compression of the slotted portion of the sleeve 42, to lock the sleeve and the valve 15 together. As shown, the sleeve 42 is slidably mounted in, and extends through, a nut 47 which threadedly engages the cross piece 50, and a valve spring 48 is provided having one end engaging the lower surface of the nut 47 and its other end engaging a suitable head 49 on the sleeve 42 so as to urge the valve 15 downwardly toward its co-operating seat.

Supported between the spaced flanges 3 and 4 of the valve body 1 are the operating levers for the air valve 14 and the fuel governing valve 15. Thus the lever 54, as shown best in Fig. 5, is mounted on a suitable bearing pin 52 and the lever 55 is similarly mounted upon a bearing pin 53, the lever 55 being provided with an opening 56 through which the valve 15 extends. Extending from lever 54 is a projection 57 adapted to contact a co-operating projection 58 extending from lever 55. Pivotal movement of the lever 54, therefore, effects movement of the lever 55 through co-operation of the projections 57 and 58, and an end portion 59 of the lever 54 is disposed to engage the pusher piece or washer 39 on the air valve 14.

In addition, the lever 54 is provided with a forked projection 60 adapted to straddle the stem of the valve 15 and to engage the lower surface of the sleeve 42. When the engine is in operation, clockwise movement of the lever 54 about its pivot pin 52 thus effects an upward movement of the valve 15 against the force of the spring 48, and at the same time effects a downward movement of the air valve 14 against the force of the spring 18. A suitable projection 61 on the lever 54, adapted to engage the cross piece 50, serves to limit counterclockwise movement of the lever 54 about its pivot.

In Figs. 1 and 2 the means for obtaining timed operation of the intake valve 68, and timed and adjustable operation of the air and fuel valves 14 and 15 is shown. The valve 68 is provided with the usual compression spring 68a and is adapted to be operated against the force of the spring by the usual rocker arm 69 and push rod 70. The rocker arm 69, as shown in Figs. 1 and 2, is pivoted on a hollow pin 71 which is fixedly mounted in a supporting bracket 72 secured to the upper surface of the cylinder head 11 by suitable studs 73.

It will of course be understood that each of the cylinders 64 is provided with a suitable exhaust valve E (Fig. 1), and suitable rocker arms 90 are provided for operating the exhaust valves. Threadedly engaging the opposite ends of the hollow pin 71, upon which the rocker arms 69

and 90 are mounted, is a pair of hollow lock-nuts 87 which serve to position the rocker arms on the hollow pin 71 and provide bearings for a control or governor shaft 86 which extends through the hollow pin 71. In Fig. 1 only the hollow pin 71 for the upper one of the two cylinders (as viewed in Fig. 1) is shown, but it will of course be understood that a similar hollow pin and similar nuts 87 are provided for supporting the rocker arms 69 and 90 associated with the other cylinder, and, as shown, the governor shaft 86 extends through both of the hollow pins 71 and is journaled therein.

Adjacent its left-hand end (as viewed in Figs. 1 and 2), each of the rocker arms 69 for operating the intake valves of the engine cylinders is provided with a pair of oppositely extending bosses which form a transverse bearing part 74. A rotating part 75, journaled in the bearing 74, is provided at one end with an extending crank pin 76. Mounted on this crank pin 76 is a substantially rectangular bearing block 77 (Fig. 2), which is adapted to be received within a fork-shaped portion of a suitable connecting rod 78. The bearing block 77 and the connecting rod 78 are normally maintained in assembled relation by a cotter pin 80 which extends therethrough. At its lower end the connecting rod 78 engages a suitable pin 79 adapted to extend through suitable apertures 79a in the forked, extending end of the valve operating lever 54, Fig. 5.

The ends of the rotatable members 75 opposite from the crank pins 76 extend outwardly from the opposite ends of the bearing members 74 on the rocker arms 69, and these extending ends are keyed to suitable forked levers 81 which carry at their outer ends cross pins 82. Each of the cross pins 82 extends through one end of an associated connecting rod 83 positioned between the respective forked ends of the members 81, the other ends of the connecting rods 83 being similarly connected, by means of pins 85, to forked levers 84, the connections at each end of the rods 83 being such that relative movement can take place between the rods and the respective supporting pins 82 and 85. The levers 84, as shown best in Fig. 1, are mounted on the governor shaft 86 adjacent the intermediate nuts 87 carried by the hollow pins 71. Intermediate the two levers 84, the governor shaft is provided with an extending lever 88 which is secured to the governor shaft and which may be suitably attached at its outer end 89 to a suitable engine governor or a hand-operating gear, not shown.

In Fig. 2 the valves and the valve operating mechanism are shown in an operating position, wherein the intake valve 68 has been opened by downward movement of the left end of the rocker arm 69, and it will be apparent that such downward movement effects, through member 75 carried by the rocker arm, the crank pin 76 thereon and the connecting rod 78, a downward movement of the outer end of the lever 54 as viewed in Fig. 5, thus effecting a clockwise movement of the lever 54 about its pivot pin 52. Such clockwise movement, as will readily be apparent from Fig. 5 effects operation of both the oil governing valve 15 and the air valve 14, and in Fig. 5 these valves are shown in their respective open positions. So long as the governing lever 88 is not moved during the power stroke, the crank pin 76 will remain in substantially the same relative position with respect to the rocker arm 69, and consequently will effect operation of the valves

14 and 15 substantially in the same manner as if the pin 76 were rigidly fixed to the rocker arm.

Preferably, the various parts of the valve-operating gear are so adjusted that when the intake valve 68 and the air valve 14 are closed, with the end portion 59 of the lever 55 resting upon the pusher piece or washer 39 and with the projections 57 and 58 in engagement, a small clearance exists between the forked projection 60 on the lever 54 and the lower face of the sleeve 42. The spring 48 then maintains the valve 15 in engagement with its seat. With such an adjustment, opening of the air valve 14 will always slightly precede opening of the fuel governing valve 15, and closure of the air valve 14 will always occur slightly later than closure of the valve 15. Consequently, during operation of the engine, and before any fuel is admitted to the fuel cup 5, air will be admitted through the valve 14 to exhaust the products of combustion remaining in the fuel cup from the previous explosion, and after the admission of fuel oil has terminated, a small amount of air is still admitted to the cup, thus assuring an ignitable and explosive mixture in the cup for ignition by the spark plug 7a.

Control of the amount of fuel admitted to the fuel cup 5 is effected simply by movement of the lever 88 which is mounted on the control or governor shaft 86. For example, if the lever 88 is moved downwardly, that is clockwise, as viewed in Fig. 2, the corresponding motion of the governor shaft 86, transmitted through the lever 84, the connecting rod 83 and the lever 81 to the member 75, will cause the crank pin 76 to move upwardly relative to the rocker arm 69. Such upward movement of the crank pin 76 will effect a corresponding counterclockwise movement of the lever 54 so as to increase the clearance between the forked projection 60 and the sleeve 42, and to provide a greater clearance between the projections 57 and 58. Consequently, the degree of valve lift imparted to both the air valve 14 and the fuel governing valve 15 will be decreased and a lesser amount of fuel oil will be admitted to the cup 5 during each cycle of operation, whereby the power of the engine will be diminished.

Further movement of the lever 88 in the same direction will cause the crank pin 76 to move to a position such that, during a complete movement of the rocker arm 69, the forked projection 60 on the lever 54 will not engage the lower face of the sleeve 42. Consequently the fuel governing valve 15 will not be operated and no fuel will be admitted to the cup 5, resulting in stoppage of the engine. Thus the valve-controlling means heretofore described constitutes not only a means for governing the admission of fuel to the engine, but also a stopping means.

When a new multiple cylinder engine, constructed as heretofore described, is started up for the first time, it is possible that slight inaccuracies in workmanship or adjustment may require correction in order that the cylinders will perform the same amount of work, and individual adjustment of each governing valve is therefore provided and may be accomplished, as heretofore indicated, by loosening the nut 46 at the top thereof and rotating the valve 15 relative to the sleeve 42 until the proper adjustment is secured.

It will now be apparent that the present invention provides a compact and readily adjustable valve gear for operating the fuel governing and air valves in an engine of the type wherein the charge of fuel is initially supplied to an ignition

cup for ignition by a spark plug to produce a resulting explosion, under the force of which the entire charge of fuel is sprayed into the cylinder for complete burning. It will of course be apparent that the above described fuel valve and valve gear may be employed in an engine otherwise similar to the described embodiment, but omitting the spark plug 7a and opening 7 in cup 5. In such case the clearance space 66 in the cylinders must be so adjusted that a sufficiently high compression will be achieved in the cylinder to effect ignition of the charge in the cup 5, and the engine will then operate as a high compression engine. By employing the spark plug or similar separately-controlled ignition means, however, it is possible, in accordance with this invention, to employ compression values below the pressure required for ignition of the fuel.

In accordance with this invention it is possible to construct an engine of low weight and manufacturing cost which will operate efficiently on relatively low-grade fuel oil and with great reliability. The invention is not limited, however, to operation with such low-grade fuel oils, but may advantageously be employed with various grades of fuels or oils including high-grade fuels such as gasoline. When it is stated that an engine operates with quality governing, it is meant that the quantity of the charge admitted to the cylinder on the suction stroke remains constant for all loads, but its quality is made poorer at light loads by throttling or cutting off of the fuel oil alone.

One of the important advantages of an engine embodying the present invention lies in the fact that the ignition quality, so to speak, of the fuel and air charge in the cup 5 is substantially independent of the main cylinder charge admitted through the cylinder intake valve. In another embodiment of the invention, the mechanism may be arranged so that a constant small quantity of oil is admitted to the fuel cup on each suction stroke of the engine, and the cylinder intake valves may be provided with suitable gas mixing devices wherein the gas only is under the control of the governor. In this case the oil admitted to the fuel cup serves as a pilot charge and the engine operates as a gas engine with so-called quality governing. The compression, therefore, is the same under high and low load, but the provision of the pilot charge in the fuel cup insures proper ignition on every stroke regardless of the load and the quality of the main charge admitted to the cylinder proper through the cylinder intake valve.

While a particular embodiment of the invention has been shown, it will be understood, of course, that the invention is not limited thereto since many modifications may be made, and it is, therefore, contemplated by the appended claims to cover any such modifications as fall within the true spirit and scope of the invention.

Having thus described my invention, what I claim and desire to secure by Letters Patent is:

1. In an internal combustion engine of the type having an ignition cup in restricted communication with the combustion space of a cylinder for providing a preliminary explosion whereby fuel is discharged from the cup into the combustion space in atomized condition, the combination of independent fuel and air valves for admitting controlled charges of fuel and air to said cup, and operating means for effecting opening and closing of said valves in timed relation such that said air valve opens prior to

said fuel valve to exhaust from said cup the residual products of combustion and said air valve is maintained open for an interval after said fuel valve closes to insure vaporization of a portion of said fuel in said cup.

2. In an internal combustion engine of the type having an ignition cup in restricted communication with the combustion space of a cylinder for providing a preliminary explosion whereby fuel is discharged from the cup into the combustion space in atomized condition, the combination of independent fuel and air valves for admitting controlled charges of fuel and air to said cup, means for operating said valves in timed relation to the cycle of said engine, and means for controlling said operating means to simultaneously vary between predetermined minimum and maximum values the lift imparted by said operating means to said valves.

3. In an internal combustion engine of the type having an ignition cup in restricted communication with the combustion space of a cylinder for providing a preliminary explosion whereby fuel is discharged from the cup into the combustion space in atomized condition, the combination of independent fuel and air valves for admitting controlled charges of fuel and air to said cup, means for operating said valves in timed relation to the cycle of said engine, and means for controlling said operating means to simultaneously and proportionately vary the air and fuel charges admitted thereby to said cup.

4. In an internal combustion engine of the type having an ignition cup in restricted communication with the combustion space of a cylinder for providing a preliminary explosion whereby fuel is discharged from the cup into the combustion space in atomized condition, the combination of independent fuel and air valves for admitting controlled charges of fuel and air to said cup, means for operating said valves in timed relation to the cycle of said engine, and means for controlling said operating means to simultaneously and proportionately vary the air and fuel charges admitted thereby to said cup, said controlling means in one extreme position adjusting said operating means for zero lift of said fuel valve whereby stoppage of said engine may be effected.

5. In an oil burning engine of the type having an ignition cup in restricted communication with the combustion space of a cylinder for providing a preliminary explosion whereby a charge of oil in the cup is discharged into the combustion space in atomized condition, and having an intake valve for admitting a quantity of air to the cylinder to support combustion of the atomized oil therein, the combination of a rocker arm for operating said intake valve in timed relation to the cycle of the engine, independent oil and air valves for admitting controlled charges of oil and air to said cup, means for operating said oil and air valves in timed relation to each other, and linkage means interconnecting said rocker arm and said valve operating means for actuating said oil and air valves in timed relation to the operation of said intake valve.

6. In an oil burning engine of the type having an ignition cup in restricted communication with the combustion space of a cylinder for providing a preliminary explosion whereby a charge of oil in the cup is discharged into the combustion space in atomized condition, and having an intake valve for admitting a quantity of air to the cylinder to support combustion of the atomized oil therein, the combination of a rocker arm for operating said intake valve in timed relation to the cycle of the engine, independent oil and air valves for admitting controlled charges of oil and air to said cup, means for operating said oil and air valves in timed relation to each other, linkage means interconnecting said rocker arm and said valve operating means for actuating said oil and air valves in timed relation to said intake valve, and means for adjusting the connection of said linkage means to said rocker arm to vary the extent of the valve operating movement imparted by said linkage means to said valve operating means.

7. In an oil burning engine of the type having an ignition cup in restricted communication with the combustion space of a cylinder for providing a preliminary explosion whereby a charge of oil in the cup is discharged into the combustion space in atomized condition, and having an intake valve for admitting a quantity of air to the cylinder to support combustion of the atomized oil therein, the combination of a rocker arm for operating said intake valve in timed relation to the cycle of the engine, independent oil and air valves for admitting controlled charges of oil and air to said cup, means for operating said oil and air valves in timed relation to each other, a crank member carried by said rocker arm, linkage means interconnecting said valve operating means and said crank member for actuating said oil and air valves upon movement of said rocker arm, and means for adjusting the relation between said crank member and said rocker arm to vary the extent of the valve operating movement imparted to said valve operating means by said movement of said rocker arm.
